UNITED STATES PATENT OFFICE.

HARLIE A. TOWNSLEY, OF NEW HAMPTON, IOWA, ASSIGNOR OF ONE-HALF TO EUGENE JULIUS FEULING, OF NEW HAMPTON, IOWA.

PACKAGE-TIE.

1,265,279.

Specification of Letters Patent.

Patented May 7, 1918.

Application filed February 11, 1916. Serial No. 77,695.

To all whom it may concern:

Be it known that I, HARLIE A. TOWNSLEY, a citizen of the United States, residing at New Hampton, in the county of Chickasaw 5 and State of Iowa, have invented certain new and useful Improvements in Package-Ties; and I do hereby declare the following to be a full, clear, and exact description of the invention, such as will enable others 10 skilled in the art to which it appertains to make and use the same.

This invention relates to improvements in package ties, and has for its primary object to provide a simple and effective means for 15 adjustably securing a chain or other linked tie about a package or other article.

With this and other objects in view, the invention consists in the novel construction, combination and arrangement of parts as 20 will be hereinafter specifically described, claimed and illustrated in the accompanying drawing, in which:

Figure 1 represents a top plan view of the improved package tie applied to use,

Fig. 2 represents an edge elevation of the tie, the chain being removed,

Fig. 3 represents a diametrical sectional view through the tie,

Fig. 4 represents a fragmental perspective 30 view of the tie, illustrating the manner of connecting the ends of the annular member in detail, and

Fig. 5 represents a fragmental plan view 35 of the package tie, illustrating the manner of adjustably fastening the chain.

Referring to the drawing in detail, wherein similar reference numerals designate corresponding parts throughout the several views, the numeral 6 indicates a flexible 40 package tie or chain constructed of a plurality of links. The link at one end of the chain 6 is connected with an annular member 7, preferably constructed of wire of adequate gage to lend requisite strength and 45 rigidity thereto. One end of the annular member 7 is flattened, as indicated at 8, and formed with an aperture 9 receiving the reduced and angularly directed opposite end 10. The relatively wide flat end 8 of the 50 annular member is prevented from accidental removal from the reduced angular end 10 by a head 11 secured to or formed integral with the reduced end 10 and dis-

posed substantially parallel to the adjacent portion of the annular member 7.

As clearly illustrated in Fig. 5, the links of the chain 6 are of elongated formation and are of such size as to receive the head 11 and permit any one of the links to be slipped over the head 11 and the reduced angular 60 end 10 of the annular member 7.

In use, the annular member 7 is placed upon the top of a package 12 in the approximate position illustrated in Fig. 1 and the chain 6 is looped one or more times in one 65 direction about the package. The loops of the chain are drawn tightly about the package 12 and one of the links adjacent the end of the last loop is slipped over the head 11 and angular end 10 of the annular member 7, 70 the head 11 preventing the accidental disengagement of the link from the angular end 10. As clearly illustrated in Fig. 3, the free or outer end of the angular extremity 10 is inclined inwardly toward the center of the 75 annular member 7 and thus the longitudinal pull upon the chain causes the link engaged with the angular end 10 to slip inwardly toward the inner end of the angular extremity 10 and against the relatively wide flat end 8 80 of the annular member 7. If preferred, the chain may be subsequently looped about the package at right angles to the first loops placed thereon and one of the links adjacent the free end of the chain may be slipped 85 over the head 11 and angular extremity 10, so as to secure the last mentioned loops of the chain in position about the package 12.

What I claim is:

1. A package tie comprising an annular member, a chain slidably connected with the annular member, an angular directed arm carried by the upper surface of said annular member, a head connected with the upper end of said arm, said chain including a plurality of links adapted to engage the angular end of angularly disposed arm, said arm being bent inwardly toward the center of said annular member to provide an inclined surface to engage the said links. 100

2. A package tie including a split ring, one end of said ring being flat and provided with an aperture, the opposite end of said ring being reduced in thickness and directed angularly and positioned in said aperture, a 105 head connected with the free end of said

angular end to prevent the removal of said angular end from the aperture, a chain including a plurality of links adapted to engage the angular end of said split ring, said head also forming means for preventing the accidental displacement of the links.

In testimony whereof I affix my signature in presence of two witnesses.

HARLIE A. TOWNSLEY.
